UNITED STATES PATENT OFFICE.

JAMES E. FLITCROFT, OF PITTSBURGH, PENNSYLVANIA, ASSIGNOR TO P. WALL MANUFACTURING SUPPLY COMPANY, OF PITTSBURGH, PENNSYLVANIA, A COPARTNERSHIP CONSISTING OF PATRICK WALL AND JAMES P. WALL.

BURNER.

1,283,133.

Specification of Letters Patent. Patented Oct. 29, 1918.

Application filed June 10, 1918. Serial No. 102,865.

To all whom it may concern:

Be it known that I, JAMES E. FLITCROFT, a citizen of the United States, residing at Pittsburgh, Allegheny county, Pennsylvania, have invented a new and useful Burner, of which the following is a full, clear, and exact description, reference being had to the accompanying drawings, forming part of this specification, in which—

10 Figure 1 is a side elevation, partially in section, of one form of my improved burner.

Fig. 2 is a vertical longitudinal section through the burner.

Fig. 3 is a section on the line III—III of 15 Fig. 2, and

Fig. 4 is a similar view on the line IV—IV of Fig. 2.

This invention relates to an improvement in burners, and is designed to provide a 20 cheap and efficient device which can readily be constructed, and in which the liquid fuel is heated within the body of the burner in order to vaporize it before passing to the burner nozzle.

25 One of the objects of my invention is to provide a burner of this character, in which the flow channels are formed by bending a piece of pipe into proper shape, and then casting a casing around a portion of the pipe 30 which might be termed the generating coil, and which casing is provided with a plurality of air inlet openings, and fuel inlet and outlet openings. Another object of my invention is to provide a device of this 35 character which will deliver a steady stream of gas without pulsation, and also to form a structure which will not clog up with what is generally known as carbonized oil.

Heretofore various attempts have been 40 made to overcome the pulsating flow of the gas, and I have found that the same can readily be overcome by inserting a coil of fine wire in the generating tube, over which the oil moves in its passage from the inlet to the 45 burner nozzle, which will break up the oil without restricting the oil passage. I have also discovered that by forming the burner structure through which the oil passes from iron or steel, and inserting an iron or steel 50 coil within the passage, that the device will not clog up, as no deposit will be formed within the passages through which the oil passes.

In the drawings the reference character 2

designates a tube having a longitudinally disposed leg 3, which is provided with threads 4 at the end for connecting the same to an oil supply. This tube is bent into circular form as shown at 5, and is then bent to form a second leg 6 which extends parallel to the leg 3 for some distance and is then bent upwardly and inwardly, as indicated at 7, the end thereof being approximately in alinement with the center of the burner. The end of the portion 7 is provided with a threaded opening for the reception of a nipple 8. Placed within the tube 2 is a helical coil 8^a which may be formed of any suitable material, but I prefer to form it of either iron or steel wire. The tube may also 70 be formed of any material, but as before stated I prefer to use iron, in order to avoid the choking of the tube. Surrounding the portion 5 of the tube 2 and portions of the legs 3 and 6 is a casing 9 which is cast around 75 the tube and is provided with an inlet 10 and an outlet 11. 12 are air inlet openings through the walls of the casing for admitting air to the casing, which is commingled with the air drawn in through the opening 10 by 80 means of the jet flow from the nipple 8.

In the form shown in the drawings the casing 9 is cast about portions of the tube 2 inclosed by the casing. By forming the passages in the manner above described, I am 85 enabled to so shape them that the oil and gas will flow through the structure in a curved path, and thereby avoid all sharp turns which tend to increase friction and permit 90 deposits to form.

In the drawings I have shown the coil 8^a continuous from one end of the tube to the other, but it will readily be understood by those familiar with the art that I may insert 95 a coil from each end of the tube.

The advantages of my invention result from the provision of a burner having a bent tube and a casing cast about said tube whereby a curved passage for the oil is formed through the burner, together with a 100 helical coil within said tube for preventing the pulsation of the gas stream. Further the provision of a burner and coil formed of iron or steel, will prevent the formation of 105 deposits within the passage therethrough.

I claim:

1. A liquid fuel burner or blow torch, comprising a tube bent upon itself and having a

- gas exit opening at one end of the tube, the other end thereof being arranged to be connected to a liquid fuel supply, and a one-piece casing shell cast around said bent portion of the tube and interlocked therewith, the arrangement being such that the casing is fixedly locked in position on the tube, substantially as described.
2. A liquid fuel burner comprising a casing or shell and a tubular member, said tubular member having two legs extending parallel to each other for a part of their length, and connected to each other at one of their ends by a single circular loop extending at right angles to the parallel portions of the legs, said casing being cast about the loop and a portion of the legs of the tubular member, to fixedly lock them to each other, one of the legs of the tubular member being arranged to be connected to a fuel supply pipe, the other leg of the tubular member being bent upwardly and inwardly in the form of a goose neck to form a gas outlet, approximately in line with the center of the casing, substantially as described.
3. A liquid fuel burner comprising a cas-

ing or shell and a tubular member, said tubular member having two legs extending parallel to each other for a part of their length, and connected to each other at one of their ends by a single circular loop extending at right angles to the parallel portions of the legs, said casing being cast about the loop and a portion of the legs of the tubular member, to fixedly lock them to each other, one of the legs of the tubular member being arranged to be connected to a fuel supply pipe, the other leg of the tubular member being bent upwardly and forwardly in the form of a goose neck to form a gas outlet approximately in line with the center of the casing, and a nipple secured in the end of said last mentioned member, substantially as described.

In testimony whereof, I have hereunto set my hand.

JAMES E. FLITCROFT.
